UNITED STATES PATENT OFFICE.

JAMES MITCHELL, OF BONILLA, SOUTH DAKOTA.

SPRING-TUG FOR HARNESS.

No. 866,501.

Specification of Letters Patent.

Patented Sept. 17, 1907.

Application filed May 9, 1907. Serial No. 372,662.

To all whom it may concern:

Be it known that I, JAMES MITCHELL, a citizen of the United States, residing at Bonilla, in the county of Beadle and State of South Dakota, have invented new and useful Improvements in Spring-Tugs for Harness, of which the following is a specification.

This invention relates to harness tugs, and it has for its objects to provide a spring tug of simple and improved construction whereby the strain upon the neck and shoulders of the draft animal will be relieved.

Further objects of the invention are to simplify and improve the construction and operation of this class of devices.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention; it being, however, understood that no limitation is necessarily made to the precise structural details therein exhibited, but that changes, alterations and modifications within the scope of the invention may be resorted to when desired.

In the drawing, Figure 1 is a side view of the improved spring tug. Fig. 2 is a side view showing the side flaps of the tug unlaced and unfolded. Fig. 3 is a longitudinal sectional view taken on the plane indicated by the line 3—3 in Fig. 2. Fig. 4 is a transverse sectional view taken on the plane indicated by the line 4—4 in Fig. 1. Fig. 5 is a detail side view of a portion of the tug with parts broken away to expose the interior construction.

Corresponding parts in the several figures are denoted by like characters of references.

The improved tug comprises in its construction a plurality of layers of leather or other suitable material including a top layer 1, a bottom layer 2 and an intermediate layer 3, which latter is provided with laterally extending side portions forming flanges or flaps 4—4. The several layers are securely connected together by means preferably including rivets 5 which also serve to secure in position adjacent to the top layer 1, a casing C composed of longitudinally grooved or channelled bottom plates 6 and 7 provided with laterally extending wings or flanges 8—9 for the passage of the rivet or fastening members 5. The wings 8 of the top plate 6 are preferably provided along the edges thereof with downturned flanges 10 disposed adjacent to and protecting the edges of the wings 9 of the bottom plate 7.

Disposed within the casing C, and projecting at one end thereof, is a tug rod or stem 11 upon which is coiled a spring 12, the ends of which abut upon shoulders 13—14 formed respectively upon the inner or rear end of the rod 11 and at the front end of the casing, the tension of the spring being exerted to maintain the rod within the casing. The projecting end of the rod 11 is provided with an eye 15 whereby it may be connected with the hames or with some other suitable part of the harness; the opposite end of the tug having a loop 16 connected therewith for a like purpose.

The wings or flaps 4—4 of the intermediate layer 3 of the tug are brought together over the casing C, and said flaps, which are provided with apertures or eyelets 17 are securely laced together by means of a thong 18 as will be clearly seen in Fig. 1.

The operation and advantages of this invention will be readily understood from the foregoing description taken in connection with the drawings hereto annexed by those skilled in the art to which it appertains. The improved tugs are preferably used to connect the traces with the hames; but they may be interposed between the traces and the whiffletrees, or used in any other desired location. When draft is exerted, the stem or rod 11 will be projected from the casing against the tension of the spring 12, thus relieving sudden strain upon the neck and shoulders of the animal.

Having thus fully described the invention, what I claim as new is:—

1. A spring tug for harness comprising a plurality of layers of material including an intermediate layer having laterally extending flaps, a casing secured adjacent to the top layer and included between said flaps, a thong or lacing cord connecting together the free edges of the flaps, and a spring actuated draft member contained in the casing.

2. In a device of the class described, a plurality of layers of material including an intermediate layer having laterally extending flaps, a casing secured adjacent to the top layer and comprising longitudinally channelled plates having laterally extending wings, the wings of one of said plates being provided with flanges disposed adjacent to the side edges of the wings of the other plate, fastening members extending through the layers of material and through the wings of the casing plates, means for connecting the free edges of the flaps which are brought together to include the casing, and a spring actuated draft member contained in the latter.

In testimony whereof, I affix my signature in presence of two witnesses.

JAMES MITCHELL.
